UNITED STATES PATENT OFFICE

ROBERT A. SCHWARTZ, OF CLEVELAND, OHIO

EXPANDING RUNNING BOARD RACK

Application filed May 23, 1929. Serial No. 365,389.

This invention relates to improvements expanding running board rack, and has for its object the provision of a serviceable and inexpensive rack adapted for permanent attachment to the running board of an automobile, and one equipped with means for insuring a considerable measure of expansion laterally, and additional means for folding the rack into inoperative position and holding it beneath the running board.

Racks of the same general character previously have been devised, but none of which I am aware is provided with means affording the wide measure of expansion and support that I have provided in my improved rack, in association with spring members for limiting the expansion and preventing rattling while the automobile is under way.

Briefly describing the rack of my invention, I may state that it comprises a frame, preferably of latticed metallic construction, having extended U-shaped clips adapted to take over and under the edge of the associated running board. This frame is provided with a plurality of hinges positioned below the plane of the running board, and a plurality of springs are provided normally to hold the U-shaped clips in close engagement with the edge of the running board. Upon these hinges, however, said frame is adapted to be rotated approximately through 270° into parallelism with, and beneath the running board so that retaining members may hold the frame retired from sight.

Details of my improved construction, together with the advantages and utilities thereof may be best explained in connection with the accompanying drawings illustrating a preferred embodiment of my invention, wherein:

Figure 1 is a side view in elevation, centrally broken away, illustrating a portion of an automobile running board with the improved rack of my invention in operative position thereon;

Fig. 2 is a transverse sectional view in line with one of the spring members, the casing of which is partially broken away;

Fig. 3 is another transverse sectional view illustrating the position of the parts either

for engaging or releasing the U-shaped supporting clip with or from the edge of the running board, and

Fig. 4 is a transverse sectional view showing the rack folded and secured beneath the running board.

Throughout the several figures of the drawings, the same character of reference is employed to indicate similar parts.

In all of the figures a running board is conventionally shown at *a*, with which my expandible rack is associated. The frame, comprising the effective side member of the rack, may be of such length as desired, and it is constructed, preferably, of riveted horizontal, vertical and diagonal metal straps, *b*, *b'* and *b''*. Upon the lower horizontal member *b* there are provided a plurality of riveted and elongated U-shaped clips *c*, adapted normally to engage snugly above and below the edge of the running board *a* and hold the frame in perpendicular relation therewith while permitting considerable lateral movement of the frame relative to the running board. Handles *d* advantageously may be secured adjacent to these clips.

A secondary horizontal member *e* is riveted to the uprights *b'* for mounting the frame in a folding position below the plane of the running board, and a plurality of hinges *e'* having their axes parallel to the longitudinal axes of the frame and running board, are provided for this purpose. There are also provided a plurality of spring-cases *f* bolted beneath the running board by bolts *f'* and respectively containing springs *f''* anchored between the bolts *f'*, *g'*; the latter connecting said springs with the longitudinal bar *g* and the hinges *e'*, in each case.

As thus constructed and equipped, the frame is adapted to be resiliently held in perpendicular relation with the running board by means of the U-shaped clips and coacting springs, and these members afford a substantial lateral expansion, measured by the length of the clips, for increasing the carrying capacity of the rack. For the device shown, this expansion is slightly less than is indicated by the relation of the parts in Fig. 3, wherein the clips are shown in released position.

tion beyond the edge of the running board. This is the position in which the rack may be released and folded beneath the running board, as shown in Fig. 4.

5. Thus, by bodily turning the frame laterally upon its hinges relative to the running board approximately through an arc of 270° , with slight retraction of the springs, as well, said frame is completely retired from view, and
 10 10 the angle-catches h , tensioned by springs h' are held beneath the outer "vertical" straps b' , and serve to retain the rack in its inoperative or non-carrying position, until again required for use. Merely by giving the
 15 15 angle-catches a quarter turn by means of their handles h'' , the frame immediately is released, and it may be adjusted in its original carrying position.

The importance of the U-shaped clips, or
 20 20 their equivalents, in association with the co-acting springs, for maintaining the rack from tilting or bulging with expanded, or heavy loads, will be appreciated. Moreover, these clips are completely disengaged from
 25 25 and retired beneath the running board, when the rack is not in use.

Having now described the structure embodying my invention in its present preferred form, I claim as new and desire to secure by Letters Patent, the following:

1. In an expansible rack for running boards, the combination with said running board, of a rigid side frame member normally located at the side edge of the running
 35 35 board, a plurality of elongated U-shaped clips fitting over the edge and engaging the upper and under surfaces of the running board, coacting springs mounted on the under surface of the running board and connected with the side frame member for holding the same in normal position, and hinge members located at the connection between the springs and the side frame member, the axes of the hinge members being parallel
 40 40 with the longitudinal axes of the running board and the side frame member, whereby the side frame member may be removed from the U-clip engagement with the running board and rotated laterally beneath the running board.

2. In a rack for running boards, the combination with said running board, of a side frame member normally located at the side edge of the running board, a running board
 55 55 mounting for the side frame member including intermediate hinged connections, whereby the side frame member may be rotated from normal position to a position beneath the running board, and releasable retaining
 60 60 means mounted on the running board and extending from the under surface to the upper surface operable from the upper surface for maintaining the side frame member in position beneath the running board.

- 65 3. In combination with an automobile

running board, a rack including a rigid side frame normally located at the side edge of the running board, means detachable by lateral movement of the side frame for connecting the side frame to the edge of the running board in perpendicular relation to the plane thereof, spring means mounted on the under surface of the running board and connected with the side frame for normally urging the side frame toward the side edge of the running board, and hinge means connected to the side frame for swinging the side frame bodily about an axis parallel with the longitudinal axes of the side frame and running board to fold the side frame beneath the running board.

4. In combination with an automobile running board, a rack including a rigid side frame normally located at the side edge of the running board, means detachable by lateral movement of the side frame for connecting the side frame to the edge of the running board in perpendicular relation to the plane thereof, spring means mounted on the under surface of the running board and connected with the side frame for normally urging the side frame toward the side edge of the running board, hinge means connected to the side frame for swinging the side frame bodily about an axis parallel with the longitudinal axes of the side frame and running board to fold the side frame beneath the running board, and releasable retaining means mounted on and extending through the running board and operable from the upper surface thereof for maintaining the side frame in position beneath the running board.

In testimony whereof I do now affix my signature.

ROBERT A. SCHWARTZ.
